CLAIM

The ornamental design for a light emitting diode lamp, as shown and described.

DESCRIPTION

FIG. 1 is a perspective view of the light emitting diode lamp. FIG. 2 is a top plan view of the light emitting diode lamp.

FIG. 3 is a side elevational view of the light emitting diode lamp, the side elevational view from all sides of the light emitting diode lamp being the same; and,

FIG. 4 is a bottom view of the light emitting diode lamp.

Any broken lines shown in FIG. 1-FIG. 4 are environmental and not part of the claimed design.

References to “side”, “top”, and “bottom” in the figure descriptions are not meant to require certain in-use orientation; a lamp according to the claimed design may be used in any orientation.
